UNITED STATES PATENT OFFICE

EDWARD HENRY MURRAY, OF FREEPORT, NEW YORK

GOLF GAME

Application filed September 18, 1930. Serial No. 482,861.

This invention relates to a golf game and has for one of its objects to provide, in a manner as hereinafter set forth, an apparatus of this character embodying an inclined area which merges, at one end, into a convoluted cup or raceway having a vertical axis around which a ball which has been driven up the inclined area is adapted to travel, said ball travelling to various points up the raceway in accordance with the force with which same has been driven.

Another important object of the invention is to provide a golf game of the character described having a plurality of holes or openings distributed over the inclined area and the race-way for the reception of the ball, each of the holes having associated therewith a branch return pipe which communicates with a common return pipe whereby the balls will gravitate to the lower end of the inclined area after dropping into the holes.

Another important object of the invention is to provide a golf game including ball actuated electric means for indicating and recording when a player has put the ball in the different holes.

Other objects of the invention are to provide, in a manner as hereinafter set forth, a golf game which will be simple in construction, strong, durable, efficient in operation and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in top plan of an apparatus constructed in accordance with this invention,

Figure 2 is a vertical longitudinal sectional view through the device,

Figure 3 is a diagrammatic view of the electric circuit and indicating means,

Figure 4 is a fragmentary detail view in vertical section of one of the ball actuated

electric switches which is located in each of the holes.

Referring to the drawings in detail, it will be seen that the apparatus constituting this invention comprises a board or playing field 55 which includes an inclined area 1 which merges, at its upper ends, into a convoluted cup or race-way having a vertical axis and designated generally by the reference numeral 2. The inclined portion 1 and the convolutions of the race-way 2 have distributed therein the holes 3 and branch return pipes 4 extends from each of the holes 3 to a common return pipe 5 through which the balls gravitate to the forward or lower end portion of the apparatus after entering the holes. 65

The playing field further includes a pocket or depression 6 which also is provided with a pair of holes 3 into which a ball which may enter the depression 6 may drop. The pocket or depression 6 is located preferably adjacent to and beneath one of the convolutions of the race-way. 70

The reference numeral 7 designates a supporting post for the race-way. The playing field further includes, at its forward end portion, a horizontally disposed portion constituting a putting area 8 having a plurality of holes 9 therein for the reception of a ball, said holes also having communication with the common return pipe 5 through the branches 10. A rail or cushion 9' is provided on three sides of the area 8 to permit a ball to be "banked" into the holes 9 should it be desired or necessary to play the shot this way. The rail 8 may be formed of suitable resilient material, such as rubber. A suitable cup or receptacle 11 is provided at the lower or discharge end of the return pipe 5 for the reception of the balls. 85

Located in each of the branch return pipes 4 and 10 is a stationary electric contact 12 which is adapted for engagement by a pivotally mounted ball actuated contact 13. As will be apparent, the contacts 12 and 13 constitute a ball actuated switch which is normally open and which is preferably located adjacent the holes 3 and 9. 95

The contacts 12 and 13 are, of course, insulated in any suitable manner from the pipes 100

4 and 10. A suitable indicator designated generally by the reference numeral 14 (see Figure 3) is located at any desired point and includes a plurality of transparent numbered 5 plates of glass behind each of which is located an electric light bulb and a suitable electrically operated recording device which is designated by the reference numeral 15.

The transparent numbered plates of the 10 indicating device are designated by the reference numeral 16 and are mounted in a suitable frame 17. The electric light bulbs (not shown) and the recording devices 15 are electrically connected with the respective 15 contacts 12 in the branch pipes 4 and 10 by the conductor wires 18 and with the contacts 19 which are arranged in a circle on the insulating disk 20 by the conductor wires 21.

Each of the contacts 19 is designated by an 20 indicating numeral 22. A contact arm 23 is centrally mounted for rotary movement on the disk 20 for selective engagement with the contacts 19 and the contact arm 23 is electrically connected with each of the pivoted contacts 13 in the branch pipes 4 and 10 by the conductor wires 24 and 25. An electric battery 26 is interposed in the wire 24.

In use, the player drives a ball up the inclined area 1 from the lower end thereof and, 30 if the ball is driven with sufficient force and does not enter one of the holes 3 on the inclined area 1, said ball will travel around the convolutions of the cup or race-way 2 and may drop into the holes which are distributed 35 on the convolutions of the race-way. The distance up the race-way which the ball may travel depends on the force with which the ball has been driven, as hereinbefore explained. Should the ball fail to enter any of 40 the holes in the race-way, same may gravitate into the pocket or depression 6 and return through the return pipe 5 to the receptacle 11.

Should the ball enter any of the holes 3 45 in the inclined area 1 or race-way 2, said ball will engage the pivoted contact 13 and swing said contact downwardly and engage same with the stationary contact 12 and thus the circuit to the indicating and recording device 14 is closed. It should be here stated that, before driving the ball, the player moves the contact arm 23 into engagement with the contact 19 which is electrically connected with the ball actuated switch constituted by the members 12 and 13 which is located in the hole into which the player may be attempting to place the ball.

Thus, when the desired hole has been made, 50 the light in the indicating device 14 which is behind the transparent numbered plate 16 which designates that hole will be illuminated and the electric current operates the recording device 15 which is associated with that particular hole for indicating that the 55 hole has been made.

When a player desires to practice putting the ball is placed on the horizontal area 8 and played into any desired one of the holes 9, as will be apparent. The ball may be played straight for the desired hole 9 or 70 may be banked from the rail 8' in case one of the other holes 9 is between the ball and the hole being played.

It is believed that the many advantages 75 of a golf game constructed in accordance with this invention will be readily understood, and although the preferred embodiment of the invention is as illustrated and described, it is to be understood that changes in the details of construction may be had 80 which will fall within the scope of the invention as claimed.

Having thus described my invention, what I claim as new is:

A game apparatus comprising a guideway 85 surface sloping upwardly from the front to the rear, and a vertically arranged spiral surface of open construction with its lower end merging into the rear end of the inclined surface and with its convolutions sloping downwardly and inwardly, a bowl forming part located under the front part of the top spiral and spaced from said front part with the side and rear bottom walls of the top convolutions connected with the top wall 90 at the rear of the bowl and pocket openings in the inclined surface, in the convolutions of the spiral and in the bottom of the bowl to which pocket openings return pipes are connected. 100

In testimony whereof I affix my signature.
EDWARD HENRY MURRAY.
